(57) **CLAIM**

The ornamental design for a template for quilting, as shown and described.

DESCRIPTION

FIG. 1 is a top surface view of my template for quilting design showing both solid and dashed lines associated with placement marks and symbols for the process of precisely cutting pieces of fabric useful in quilting; and wherein the solid, dashed lines and symbols are measuring and visual guides. The dashed lines are not for illustrative purposes, but rather indicate stitching locations in different shapes as visual aids for a quilter using my template for quilting design invention; FIG. 2 is a bottom edge view of my template for quilting with the top edge view being the same;

FIG. 3 is a right side edge view of my template for quilting; FIG. 4 is a left edge view of my template for quilting; and, FIG. 5 is a bottom surface view of my template for quilting design showing the top surface lines and guidance symbols in reverse position when viewed through the clear acrylic of the template for quilting design invention. Otherwise, the bottom view is flat and lacking in any ornamentation.

1 Claim, 2 Drawing Sheets
